[57] CLAIM

The ornamental design for a case for powder, as shown and described.

DESCRIPTION

FIG. 1 is a front view of a case for powder showing my new design, the rear view being identical to the front view;

FIG. 2 is a top plan view thereof;

FIG. 3 is a right side view thereof, the left side view being identical to the right side view;

FIG. 4 is a bottom plan view thereof;

FIG. 5 is a cross sectional view taken along line 5—5 in FIG. 1; and,

FIG. 6 is a perspective view thereof.
